CLAIM

We claim the ornamental design for a drug delivery device, as shown and described.

DESCRIPTION

FIG. 1 is a perspective view from above of an embodiment of the claimed design;

FIG. 2 is a perspective view from below of the claimed design;

FIG. 3 is a front view of the claimed design;

FIG. 4 is a rear view of the claimed design;

FIG. 5 is a right side view of the claimed design;

FIG. 6 is a left side view of the claimed design;

FIG. 7 is a top view of the claimed design; and,

FIG. 8 is a bottom view of the claimed design.

The broken line showing of parts of the drawings is included for the purpose of illustrating use and environment and forms no part of the claimed design.

1 Claim, 4 Drawing Sheets
